OTHER PUBLICATIONS

U.S. Appl. No. 29/398,195, filed Jul. 27, 2011, by Gehrke et al. for "Outer Cover For An Absorbent Article".

* cited by examiner

Primary Examiner — T. Chase Nelson

Assistant Examiner — Michelle E Wilson

(74) *Attorney, Agent, or Firm* — Sarah Ann Dressel

(57) **CLAIM**

We claim the ornamental design for an outer cover for an absorbent article, as shown and described.

DESCRIPTION

The sole FIGURE is a development view of an outer cover for an absorbent article showing our new design.

The alternating short and long dashed lines shown around the perimeter of the outer cover of an absorbent article are included for the purpose of depicting environment and form no part of the claimed design.
